CLAIM

The ornamental design for a protective folio with keyboard for multiple types of input devices, as shown and described.

DESCRIPTION

FIG. 1 is a perspective view of a first embodiment of our protective folio with keyboard for multiple types of input devices showing our new design in an open configuration; FIG. 2 is a top plan view thereof; FIG. 3 is a bottom plan view thereof; FIG. 4 is a front elevational view thereof; FIG. 5 is a rear elevational view thereof; FIG. 6 is a left side elevational view thereof; FIG. 7 is a right side elevational view thereof; and, FIG. 8 is a perspective view showing the first embodiment of our new design in a closed configuration.

FIG. 9 is a perspective view of a second embodiment of our protective folio with keyboard for multiple types of input devices showing our new design in an open configuration; FIG. 10 is a top plan view thereof; FIG. 11 is a bottom plan view thereof; FIG. 12 is a front elevational view thereof; FIG. 13 is a back elevational view thereof; FIG. 14 is a left side elevational view thereof; FIG. 15 is a right side elevational view thereof; and, FIG. 16 is a perspective view showing the second embodiment of our new design in a closed configuration.

The broken lines in the drawings depict environmental subject matter/or parts of the protective folio with keyboard for multiple types of input devices and form no part of the claimed design.
